DISPENSER CLOSURE FOR BOTTLES

Lester L. Lewis, Cabot, Pa.

Application February 25, 1948, Serial No. 10,880

2 Claims. (Cl. 215—16)

2

This invention relates to a dispenser closure for bottles, flasks and the like, and more particularly to a dispensing closure so constructed as to render difficult the introduction of any material from the exterior to dilute or replace the contents of the vessel.

An object of the invention is to provide an improved and simplified dispensing stopper for bottles, flasks and the like, which will permit the withdrawal of the fluid contents from the bottle in measured amounts, and which will render difficult the introduction of adulterants or refill material into the container.

The invention consists in the novel construction, arrangement and combinations of parts hereinafter more particularly described and claimed.

Two sheets of drawings accompany this specification as part thereof, in which like reference characters indicate like parts throughout.

In the drawings:

Figure 1 is a fragmentary longitudinal cross section through the neck end of a bottle closed with the present measuring device, and illustrating the initial position of the device in the operation of withdrawing the contents of the bottle;

Figure 2 is a similar cross section to Figure 1, illustrating the second step in the operation of withdrawing the contents of the bottle;

Figure 3 is a longitudinal cross section through the improved metering device;

Figure 4 is a longitudinal cross section partly in elevation showing a modified structure;

Figure 5 is a perspective view of the abutment member removed from the metering device; and

Figure 6 is an exploded perspective of the modified form of abutment member.

In accordance with the present invention, two cup-like members 1 and 2, each having one end closed or partially closed, and substantially cylindrical chambers, are associated by abutting their open ends against peripheral portions of a central abutment member 14 which for this purpose is preferably formed with an annular rib 15 adapted to space the adjacent end portions of the cups 1 and 2, which may be conveniently cemented or otherwise secured thereto.

The abutment member 14 is provided with an axially positioned bore 16 and spaced around the bore 16 are a plurality of passages 18 through which the fluid contents of the bottle is adapted to pass. These outlet passages 18 are provided with flapper valves 19 mounted upon the outer face of the abutment member, and one orifice is

associated with an inlet valve 17 to permit the admission of air into the flask or bottle to replace the fluid as withdrawn.

In the form shown in Figure 6, a single disk valve 21 is provided which is guided with respect to the abutment member 14 as by headed pins 23 and compression springs 24. With this type of valve there is sufficient leakage of air to avoid the necessity for an air inlet valve.

10 The innermost cup-like member 2 is provided with laterally disposed ports 13 spaced sufficiently above the bottom 12 to clear a piston 11 slidable in the cylindrical bore of this member when said piston 11 is in its innermost position, as illustrated in Figure 3.

The piston 11 is associated with a piston rod 1' which is threadedly associated with an extension tubular portion 7 which extends slidably through a bore 6 in the top or cap portion 3 of the 20 cup-like member 1, the upper end of the tube 7 being threadedly associated with a Y-shaped finger grip 9 having oppositely disposed arms 10, both the finger grip 9 and the arms 10 being provided with converging bores which communicate with the bore of the tube 7. The tube 7 is provided with a lateral port 27 positioned with respect to the piston 11 so as to be exposed within the bore of cup member 1 only when the piston 11 is in its innermost position, and as illustrated 25 in Figure 3.

The head or cap portion 3 of cup 1 is exteriorly threaded to receive a cap 4 and a rubber gasket 8 is positioned between the top or cap 3 and the inner face of closure cap 4, surrounding tube 7 to 30 make a tight sliding fit for this tube through the head of the device.

A compressible gasket 20 of rubber or the like is positioned around the cup members 1 and 2 so as to make a sealing fit with the neck of the 35 bottle when these parts are inserted as a stopper in the usual manner.

In the modified form of the device illustrated in Figure 4, it is proposed making the unit in a single piece by stamping same from plastic or 45 the like, thereby eliminating the separate abutment member 14 and forming the abutment 14' integral with the cylindrical structure which is stamped to provide axially aligned cylindrical chambers similar in all respects to those illustrated in Figure 3.

The operation of the device will be apparent from a consideration of Figures 1 and 2. To discharge fluid from the bottle, the bottle is inverted, as illustrated in Figure 1, with the piston 50 11 in its innermost position, in which posture

3

it will be apparent that the liquid in the bottle will enter the innermost chamber through ports 13, thus filling that chamber. Thereupon, by grasping the hand discharge spouts 10 and pulling the piston 11 to its outermost position, the liquid will be forced from the innermost compartment through the orifices 18 in abutment 14 and against flapper valves 19 to fill the outermost chamber. It will be observed that in drawing the piston 11 from its innermost to its outermost position, the port 27 in tubular piston rod 7 will have been withdrawn at the very beginning of the stroke beyond the top or cap 3, thereby preventing any escape of liquid from the outer compartment during this operation. With the outer compartment filled with liquid, as illustrated in Figure 2, the piston 11 will be again forced inwardly to its innermost position, thereby returning port 27 to communication with the outer chamber and permitting the fluid in said outer chamber to escape through said port 27, the tubular piston rod 7 and the discharge spouts 10. When this metered amount of the liquid has been thus drained from the outermost compartment, air can replace the liquid in the outermost compartment, and upon repetition of the cycle thus described, this air will be permitted to enter the bottle through the valve 17, thus replacing the liquid in the bottle.

The precise structure of the various parts can be modified to suit particular containers and situations, but within the scope of the present invention as claimed.

Having thus fully described my invention, I claim:

1. Dispensing closure for bottles and the like comprising, a stopper-like member adapted to seal the neck of the bottle, said member formed with axially aligned chambers separated by an

with small, angled chambers separated by an

...durch einen geschäftlichen oder sozialen Kontakt mit dem Betreiber einer Firma in Südtirol, der dem Betrieb der Firma in Südtirol eine gewisse Menge an Waren oder Dienstleistungen zufließen lässt.

abutment having valve controlled through passages, a piston slideable in the inner chamber, a piston rod extending slidably from the piston through the abutment to the exterior of the outer chamber, the outer portion of the piston rod being hollow and communicating with the interior of the outer chamber only when the piston is in its innermost position, the inner chamber having ports communicating with the interior of the bottle, said ports located to clear the piston in its innermost position.

2. Dispensing closure for bottles comprising, a stopper-like member adapted to seal the neck of the bottle, said member formed with axially aligned chambers separated by an abutment wall having valve controlled passages to permit entry of air into the inner chamber and the passage of the fluid contents of the bottle into the outer chamber, a piston slidable in the inner chamber having a rod extending slidably through the abutment and the outer wall of the outer chamber, the outer portion of the piston rod formed with a bore communicating through a lateral port with the interior of the outer chamber immediately adjacent the outer wall of said chamber when the piston is in its innermost position, the wall of the inner chamber formed with inlet ports located above the piston when in its innermost position.
